UNITED STATES PATENT OFFICE

JAMES A. NOONAN, OF LOWELL, MASSACHUSETTS, ASSIGNOR TO C. G. SARGENT'S SONS CORPORATION, OF GRANITEVILLE, MASSACHUSETTS, A CORPORATION OF MASSACHUSETTS

APPARATUS FOR COVERING ROLLS WITH TOOTHED WIRE

Application filed January 7, 1930. Serial No. 419,171.

The principal objects of this invention are to provide mechanism whereby cylindrical ungrooved rolls can be covered with toothed wire which has a rectangular cross-section with its height materially greater than its width; to provide means whereby each strand of wire as it is wound will be held against the next strand firmly but yieldingly so that it will not get out of place or tip over, thus necessitating the stopping of the machine and the straightening of the wire by hand; to provide means for eliminating the hammering of the strands together which has been a necessary heretofore and which has been a slow and unsatisfactory job; and to provide a continuous and automatic means for winding the wire, thus greatly expediting the operation.

Other objects and advantages of the invention will appear hereinafter.

Reference is to be had to the accompanying drawings, in which.

Fig. 1 is a side view of a machine constructed in accordance with this invention shown in operation;

Fig. 2 is a sectional view on the line 2—2 of Fig. 1 showing the winding apparatus itself in end elevation;

Fig. 3 is a detail sectional view showing the means for continuously pushing each strand up against the next one;

Fig. 4 is a sectional view of the cylinder showing one form of toothed wire applied thereto by this apparatus; and

Fig. 5 is a sectional view on the line 5—5 of Fig. 1 showing the adjustment of the feeding-in guide roll.

For the purpose of making garnetting cylinders and the like of toothed wire of a character similar to that shown in Fig. 4, it has usually been necessary to cut a helical groove in the cylinder involving an expenditure of time which would be entirely eliminated if the wire could be wound on an ungrooved cylinder. Attempts have been made to accomplish that result but they have been crude and the wire has always had a tendency to tip over or to leave spaces between the strands. This necessitated the stopping of the machine and the straightening of the

wire by hand hammering. This made the process slow and the completed job could not be satisfactory.

This machine is designed to accomplish the work very rapidly and avoid the delays in grooving the cylinder and straightening the wires on its surface. With this machine the wires are arranged in proper place and all tendency for them to tip over or be wound with spaces between the strands is avoided. This is done by holding each strand firmly but yieldingly in place as it is laid on the cylinder.

For the purpose of carrying out this invention, I provide what is practically a lathe having head and tail centers for the smooth cylinder 11 on which the wire is to be wound. This cylinder is rotated as the work is usually rotated in lathes. I provide both on the front and rear a carriage 9 each carrying a tool slide 12 operated in the usual way in the case of a lathe by a feed-screw 13 on the front of the lathe. The carriage is connected across so that it controls both of the tool slides.

On each tool slide is a tool holder 14 but in place of a tool this holder carries a bar 15. The two bars 15, placed preferably diametrically opposite each other at the sides of the cylinder 11, carry the two halves 16 of a complete ring. These two halves are firmly secured to the two bars 15 and they are also preferably secured together by straps 17. Through this ring 16 are passages for receiving rods 18 which are freely slidable therein and have heads or collars 19 to limit their motion in one direction. Each rod is provided with a coil spring 20 on its surface which bears on one end on the ring 16 and at the other end on a flange 21 carried by a second ring 22. This is a split ring with its ends held together by a bolt 27. Each rod 18 is provided with a reduced screw-threaded end 23 which is held to the flange 21 by a nut 24. As these flanges 21 are firmly secured to the ring 22, that ring will be forced forward by spring pressure. It bears on the last laid strand or convolution of the toothed wire 25 wound on the cylinder.

It will be obvious that, as the cylinder is

turned and the feed of the tool holders maintained in the proper relationship to the rotation of the cylinder, the wire properly fed will be wound on the cylinder in layers, as indicated in Figs. 1 and 3, and always held up against the shoulder 26 on the cylinder by the ring 22. This ring is pressed forward with a yielding pressure due to the springs and at all times this pressure is exerted so that the machine automatically prevents the wire from tipping over and spreading on the cylinder. These two sources of delay are entirely eliminated and there is no necessity for previously grooving the cylinder. Thus two important elements of the cost of winding these cylinders or rolls are done away with. Also the product is practically mechanical and irregularities in the winding are eliminated.

20 For the purpose of guiding the toothed wire from a reel or coil on which it is located, a guide wheel 30 is employed mounted on a bracket 31 which is pivotally mounted on a vertical stud 32 on a base 33. It is 25 adapted to be adjusted through a bolt and slot arrangement 34 at the top of the carriage 9 on the front of the machine. The wire also passes through a guide 35 which is fixed on one of the flanges 21 on the ring 30 22 and in this case it travels along with this ring and the bracket as they are both mounted to be controlled directly or indirectly by the feed-screw 13.

Although I have illustrated and described 35 only one form of the invention, I am aware of the fact that modifications can be made therein by any person skilled in the art without departing from the scope of the invention as expressed in the claims. Therefore 40 I do not wish to be limited to the exact form shown but what I do claim is:—

1. In a machine for winding toothed wire on a smooth cylinder, the combination with means for rotating the cylinder, of a feed screw, a tool slide mounted on each side of the cylinder and both controlled by said feed screw to move along the cylinder at a predetermined rate, a pair of tool holders carried by said tool slide, a ring surrounding the cylinder, means in the tool holders for supporting the opposite sides of said ring, a second ring surrounding the cylinder arranged close to its surface, and yielding means supported by the first ring for holding the second ring 55 into position for holding each convolution of wire in position as the wire is wound.

2. In a machine for winding toothed wire on smooth cylindrical surfaces, the combination with means for rotating the cylinder, a tool slide mounted on each side of the cylinder and both controlled to move along the cylinder at a predetermined rate, a pair of tool holders carried by said tool slides, a member carried by the tool holders, a ring 60 surrounding the cylinder arranged close to its

surface, and yielding means supported by said member for forcing the ring against each convolution of wire on the cylinder as the wire is wound.

3. In a machine of the character described, 70 the combination with a tool post and means for moving it along, of a bar carried by the tool post, a ring supported by said bar, springs carried by the ring, and a second ring spaced from the first for engaging the convolution of wire being wound and exerting a yielding pressure thereon.

4. In a machine of the character described, 80 the combination with a machine of lathe type having centers for supporting a cylinder and having a tool slide and means for operating the tool slide at a predetermined rate, of means carried by the tool slide for exerting a constant yielding pressure on each convolution of wire to hold it on the cylinder 85 in position while being wound, and a wire guide mounted to move with the tool slide for guiding the wire into position adjacent to said means.

5. In a machine of the character described, 90 the combination of a ring adapted to surround a cylinder to be operated upon, said ring having longitudinal passages therethrough, rods slidably mounted in said passages, a spring on each rod, a second ring spaced from the first and parallel therewith having flanges projecting therefrom in which the ends of said rods are fixed, whereby the springs force the second ring along the cylinder during the operation of the machine, and 100 movable means for supporting the first ring and moving it along the cylinder during the winding operation.

6. In a machine of the character described, 105 the combination of a ring adapted to surround a cylinder to be operated upon, a second ring spaced from and connected with the first and parallel therewith, means for forcing the second ring along the cylinder during the operation of the machine, and 110 movable means for supporting the first ring and moving it along the cylinder during the winding operation.

In testimony whereof I have hereunto affixed my signature.

JAMES A. NOONAN.
